US00D577066S

(12) **United States Design Patent**
Zhao et al.

(10) **Patent No.:** US D577,066 S
(45) **Date of Patent:** ** Sep. 16, 2008

(54) **PEN**

(75) Inventors: **Feng Zhao**, Ningbo (CN); **Yuemin Shi**, Ningbo (CN)

(73) Assignee: **Beifa Group Co., Ltd.**, Ningbo (CN)

(**) Term: **14 Years**

(21) Appl. No.: **29/276,199**

(22) Filed: **Jan. 18, 2007**

(30) **Foreign Application Priority Data**

Jul. 18, 2006 (CN) 2006 3 0122800

(51) **LOC (8) Cl.** 19-06

(52) **U.S. Cl.** D19/50

(58) **Field of Classification Search** ..... D19/35, D19/36, 41-51, 53-57; 24/11 F, 11 P, 11 R; 401/52, 99, 100, 104-109, 192, 195, 196

See application file for complete search history.
